UNITED STATES PATENT OFFICE.

RICHARD TEICHMANN, OF BROOKLYN, NEW YORK.

BURGLAR-ALARM.

SPECIFICATION forming part of Letters Patent No. 391,724, dated October 23, 1888.

Application filed December 9, 1887. Serial No. 257,417. (No model.)

To all whom it may concern:

Be it known that I, RICHARD TEICHMANN, of Brooklyn, in the county of Kings and State of New York, have invented certain new and 5 useful Improvements in Burglar-Alarms, of which the following is a specification.

This invention relates to an improved burglar-alarm that is operated by the turning of the knob and either applied to the door or 10 made portable, the alarm being of simple, cheap, and effective construction; and the invention consists of a burglar-alarm that comprises a bell, a fixed spindle, a sleeve mounted on said spindle, a spiral spring attached to the 15 spindle and sleeve, a clapper pivoted to an eye of the sleeve, a string which is wound around the sleeve and provided at the opposite end with a hook, so that by pulling the hook the string is unwound and the spring set 20 to tension, while when the hook is released the return of the spring to its normal position turns the sleeve, operating the clapper in turning the sleeve so as to ring the bell.

In the accompanying drawings, Figures 1 25 and 2 represent two different modifications of my improved burglar-alarm, shown as applied for use. Figs. 3 and 4 represent, respectively, a front elevation with a part broken away and a vertical transverse section of the alarm shown 30 in Fig. 1; and Fig. 5 is a vertical transverse section of the alarm shown in Fig. 2.

Similar letters of reference indicate corresponding parts.

My improved burglar-alarm may either be 35 used by being permanently attached to the door or door-casing or by being made portable, so as to be carried along in the trunk in traveling. The main elements employed in the construction of the alarm are the same in both 40 constructions.

The alarm consists of a bell, *a*, that is mounted on a frame, or directly attached to a spindle, *b*, as shown in Fig. 3. The spindle *b* is either mounted on a base piece, *c*, which is 45 screwed to the door-casing, as shown in Figs. 1 and 3, or directly to the door by means of a threaded shank, screw-nut, and jam-nut, as shown in Fig. 5. On the spindle *b* is mounted a cylindrical sleeve, *d*, between which and the 50 spindle is arranged a spiral spring, *e*, one end of which is attached to the spindle, while the other end is attached to the sleeve, as shown

in the drawings. To the sleeve *d* is applied, by means of a fixed eye, *d'*, a loosely-swinging clapper, *e'*, which strikes the bell quickly when the sleeve rotates on the spindle. A string, *f*, is attached at one end to the sleeve and wound around the same and provided at its outer end with a wire hook, *f'*. The string *f* is guided either by a suitable eye or by a hole in the 60 body of the bell.

The alarm may be used in different ways, either by attaching it permanently to the door or other point of support or by placing it on the floor, pulling out the setting-string, and 65 applying the hook to the door-knob in such a manner that by the least turning of the knob the hook slips off and permits the spring to turn the sleeve, rewind the string, and ring the bell. In this manner a stationary or portable 70 burglar-alarm of simple, cheap, and effective construction is obtained, which can be readily set in position for use, and which resets itself by the simple act of pulling the string into the required position without the use of a winding- 75 key or other device.

Having thus described my invention, I claim as new and desire to secure by Letters Patent—

1. The combination of a bell, a fixed spindle, a rotary and spring-actuated sleeve mounted 80 on said spindle, a clapper hung to an eye of the sleeve, a setting-string attached to the sleeve, and a setting-hook applied to the outer end of the string, said setting-hook being adapted to engage the knob of the door and 85 release it when the knob is turned, substantially as set forth.

2. The combination of a bell, a spindle, a loose sleeve on said spindle, a spiral spring connected to the spindle and sleeve, a clapper 90 applied to an eye of the sleeve, a setting-string attached to the sleeve, and a setting-hook attached to the outer end of the cord, said setting-hook being adapted to engage the knob of a door and release it when the knob is turned, 95 substantially as set forth.

In testimony that I claim the foregoing as my invention I have signed my name in presence of two subscribing witnesses.

RICHARD TEICHMANN.
